APPARATUS FOR WASHING

Henry L. Alexander, Wilmington, Del., and Willing B. Foulke, Media, Pa., assignors, by mesne assignments, to Delaware Chemical Engineering and Development Company, Wilmington, Del., a corporation of Delaware

Application August 3¹, 1936, Serial No. 98,820

4 Claims. (Cl. 209—269)

This invention relates to the washing of coal and in its broadest application to the removal from solids of adhering liquids, particularly of organic type.

5 Coal appears to have been known to, and to some small extent used by, the ancients. Its use in China at about the year 1200 is described by Marco Polo and about 1500 Agricola described a process of freeing minerals from their gangue 10 which is the direct progenitor of the jig process of coal cleaning, which has the widest use today. In the early days of coal mining in Europe and in the United States only the thick seams were mined. Hand methods were largely in vogue and 15 the need for anything except hand cleaning, or the most crude of mechanical methods was unnecessary. As the thick seams were used up, however, it became necessary to use thin seams and seams containing veins of rock, which entailed the necessity of removing the rock before 20 the coal could be sold. The method which came most prominently into use and which is today the standard of separating coal and slate depends upon the rates at which bodies of different densities sink through a liquid such as water. It is 25 known that bodies sink through a liquid at rates which are functions of their respective densities, the denser sink the more swiftly. The standard jig washer of the industry takes advantage of this principle, but instead of permitting the solids to sink through the liquid, the liquid is forced 30 through a screen on which the solids rest at a rate which lifts the layer of coal off the heavier slate, the coal being carried with the rush of liquid over a weir and the slate being discharged 35 at a lower point from the screen. Jigs are highly developed and are of excellent capacity and performance. However, the competition of oil has driven coal producers to find means of cleaning 40 coal which will be more accurate in separating useful from useless lumps and producers and inventors have turned their thoughts to those processes of separation which depend upon the parting action of a liquid having specific gravity 45 between that of coal and that of slate.

The use of a parting liquid is to be distinguished from froth flotation. Froth flotation alters the apparent specific gravity of a body by encasing it within a bubble. Parting processes, 50 however, depend upon the use of a parting liquid in which one ingredient of the mixture will sink down and another ingredient of the mixture will rise to and float on the top. Certain phases of the parting liquid process are affected by the

phenomenon of altered specific gravity but they are distinguished from froth flotation.

The suggestion was made toward the middle of the nineteenth century that ferric chloride or sulfuric acid could be used as a parting liquid 5 for the separation of coal and slate and attempts were made in England to run the ferric chloride process in competition with the jigs, but the jigs were highly developed, the use of a parting liquid was a bare suggestion and the attempt was a 10 failure because of the undeveloped state of the new process, the highly developed state of jig separation, and the inability of experimenters to make the parting process a success in itself. The original attempt having been made, however, subsequent inventors worked with the suggested process and a host of patents have been issued, particularly in England and in the United States, dealing with processes of the parting liquid type. To the best of our knowledge and belief, however, 15 the only such process that has been used successfully is one that depends upon the parting effect of a suspension of solids such as sand or clay in water. The art with respect to parting media of homogeneous character is in the industry today 20 as it was in the nineteenth century, unable to compete. The parting liquids are worth more than the coal and the losses thereof are so great that they outweigh the theoretical advantages of 25 more accurate separation. The processes themselves, being crude and undeveloped, are incapable 30 of competing with the highly developed processes already in use in the industry. They are incomplete processes, lacking a number of elements essential to success.

35 It is an object of this invention to separate coal from slate, and other minerals from their gangues or from each other, by a process which depends upon the parting effect of a liquid of intermediate specific gravity. Another object of 40 the invention is to remove parting liquid of halogenated hydrocarbon or other type from the surface of coal or any other mineral that has been immersed therein or coated therewith, and to 45 provide efficient apparatus for that purpose.

The objects of the invention are accomplished, generally speaking, by subjecting the separated materials to vigorous washing with water while so acting upon the materials that all portions 50 thereof are exposed to the effect of the washing fluid. The objects of the invention are also accomplished by effecting the washing under hermetical seal. The objects of the invention are to a certain extent accomplished by the apparatus 55

and by the individual details thereof as more fully hereinafter described.

Figure 1 is an elevational view partly broken away and in section showing the scrubbing apparatus; Figure 1—a is a section on the line 1—a 1—a of Figure 1; Figure 1—b is an enlarged section on the line 1—b, 1—b of Figure 1—d, the left hand section of Figure 1—b taken on the line Z—Z of Figure 1—d; the middle section of Figure 1—b being taken on the line Y—Y of Figure 1—d; and the right hand section of Figure 1—b being taken on the line X—X of Figure 1—d; Figure 1—c is a section on the line 1—c, 1—c of Figure 1; Figure 1—d is an enlarged 15 section of the sealing mechanism shown in Figure 1—c; Figure 1—e is an enlarged section of a spray pipe with nozzles showing the overlap of the sprays.

Figure 2 discloses the apparatus for receiving material discharged from the scrubbing process, for sealing the scrubbing process, and for discharging the material.

After the coal has been separated from the indigenous impurities, both are subjected to a vigorous scrubbing. In order to prevent the loss of any liquid by evaporation or otherwise the scrubbing is preferably carried out in a hermetically sealed chamber. A shaker screen is used in order to make possible the thorough washing of the coal, and the problem of transmitting power to the screen without opening the apparatus to the air was no small one. It was accomplished, however, by the means which are more fully described below. Briefly stated, the coal is carried through an hermetically sealed connection from the separating apparatus into the washing section where, constantly tumbled about by a shaker screen, it is subjected to an extremely vigorous washing whereby to remove all fine particles and substantially all the liquids that have been used in the process. The coal and slate are then dropped from the screen into the water baths of water sealed conveyors. The used liquid is run over a concentrating table, which tends to precipitate suspended solids, and to form larger aggregates of suspended liquids, and the whole runs to the tank which forms the bottom of the machine, where a weir divides the liquids which contain only light suspended solids from the heavy sludge. The divisions are respectively drawn off and treated in a recovery system which will be more completely elsewhere described.

In the drawings Figures 1 to 1—e are illustrative of this portion of the invention. In the figures, 4 refers generally to the washing apparatus; 40 is a shaker screen; 41 is a coal trough forming part of the said screen; 42 is a slate trough forming part of the said screen; 43 is a partition dividing the screen into two sections longitudinally whereby to keep the separated coal and slate from becoming intermingled. 44 are strips of wood or some similar material which is capable of withstanding the abrasive action of the coal and slate; 45 is a foraminous section at the charging end of the screen which permits the draining of liquid; 46 is a wedge-wire screen which forms the floor of that section of the screen which approaches the discharge end; 47 is a solid bottom to the screen at the discharge; 48 are discharge lips.

The construction of the screen is as follows: Angle irons 49 form the side frames of the screen and extend longitudinally from the feeding troughs to the discharge plate 47. Dividing member 43 is also an angle iron extending from

the troughs to the pipe; 400 are angle members connecting the side frames of the machine to the main frame of the screen; 401—401 are J-shaped members having the taller leg of the J of considerable height; 402—402 are braces connecting the frame member 43 with the lower portions of the J-shaped member; 403 is a brace directly connecting the two J-shaped members; 404 is a splash guard running the length of the foraminous portion of the screen.

405—405 represent the support for the entire washing section; 406 is a tank forming the base of the machine; 407 is one wall of the tank; 408—408 are angle-shaped members forming channels with 407 and 416 respectively running lengthwise of and within the wall 407 and 416; 409 is the inclined bottom of the tank; 410 is a wall of the tank running lengthwise of the apparatus and forming a weir which divides the tank into two sections; 411 is the bottom of the tank 20 beyond the weir; 412 is the outer wall of the tank, in this case placed considerably beyond the outer wall of the screen section; 413 is the top of the said extended side; 414 is a rectangular opening, channel-shaped in cross-section, forming a seat 25 for cover 415. By filling the channel-shaped member partly with water an effective gas seal is created. 416 is a wall forming in part the outer wall of the apparatus and in part a wall dividing the two compartments of the tank; 417 are braces 30 attached on the inside to channels 408; 418 is a bar supported by braces 417; 419 are side plates extending lengthwise one on each side of the apparatus; 421 are side plates attached to the braces 402—403 running lengthwise on each side 35 of the apparatus and overlapping the upright portions of channel members 408 inwardly thereof; 420 are drain guards attached to members 419 to prevent the drainage from the screen from running into the channels 408; 422 are drain 40 guards attached to the walls of the screen chamber and projecting within the channels formed at the edges of the screen by angle members 49 and J-shaped members 401—401; 423—423 are walls 45 of the screen section of the apparatus; 424 is the top of the apparatus; 425 is a cover for an opening in the top of the apparatus, said cover being formed with one continuous flange 426; 427 are continuous channels in the top of the apparatus of size such that the continuous flange of the top 425 may be seated in the channel which, being partly filled with liquid forms an effective hermetical seal. 428—428 are supports attached to and projecting at right angles to the outer legs of the J-shaped members; 429—429 are wooden 55 spring boards; 430 are beams to which the spring boards are bolted; 431—431 are spring boards suspended from the beams 430; 432 are weights hung from the said spring board; 433—433 are guides mounted on the frame 405 of the apparatus; 434—434 are buffer members approaching the counterweights; 435 is a shaft journaled in the frame 405; 436 is a wheel capable of being driven by a belt or similar power-transmitting means and, being keyed to the shaft 435, capable 60 of driving the said shaft; 437—437 are eccentrics; 438—438 are driving rods attached to the eccentrics 437 and attached through connections 439 to the J-shaped screen frames; 440 are eccentrics placed on the shaft opposite to eccentrics 437 and 70 on the outer sides of the frames 405 respectively; 441—441 are driving rods connecting the eccentrics to the counterweights 432. The eccentrics, frame, and driving gear at the discharge end of the machine are shown broken away to indicate 75

that in practice they are farther away from the tank than was permitted to be shown in the drawing.

- 442—442 are headers which may be suspended 5 from the beams 430 by connections 443 which comprise a band encircling the header having a hook to pierce an eye on a middle strip connected to the beams 430; 444 are pipes connected to the headers entering the washing tank through hermetical seals 445; 446 are valves in the pipes 444; 10 447 are pressure gauges operatively connected to the pipes 444; 448 are pipes connected horizontally to pipes 444; 449 are spray nozzles affixed to pipes 448 so that the liquid in pipes 448 may be directed at the most efficient angle upon the material on screen 40; 450 are supports attached to the tank at spaced intervals; 451 are baffle plates supported by supports 450 extending transversely of the tank; 452 are channels at the bottom of the 15 baffle to catch the drip and direct it to the sides of the screen into the channels formed by angles 49 and sides 401 of the frame; 453 are a series of supports extending transversely between walls 407—416 of the machine and inclined with respect 20 to the horizontal; 454 is a plate supported on supports 453, extending substantially the full length of the machine, inclined by the inclination of supports 453 and terminating short of wall 416; 455 are supports which also extend between the wall 25 416 and wall 407 and which have inclination opposite to that of supports 453; 456 is a riffle plate substantially co-extensive with the length of the machine and extending from the wall 416 to a line short of the wall 407.
- 30 35 In Figure 1—a the screen is broken away at 454 to show the plain incline plate 454; at 456 on the same figure the screen and plate 454 are broken away to show the riffle plate 456 and the diagonal placement of the riffle bars. 457 is an outlet at the bottom of the tank 406 and at the juncture of incline plate 409 and weir 410; 458 40 is a pipe opening out of the portion of the tank beyond the wier; 459 is a blow-out pipe through which water under pressure can be directed to 45 discharge the sludge from the bottom of the tank through the orifices 457; 460 is a baffle plate at the end of the channel formed by members 49 and 401; 461 is a channel cut through members 49—49 so that any fluid in said channel member may be 50 discharged upon the surface of and pass through a foraminous portion of the screen; 462 is a boot beneath the discharge end 47 of the screen, separated from the tank as shown in Figure 4 and divided at its center by partition 463 which prevents the mingling of coal and slate.
- 55 60 In Figure 1—e is shown the placement of the spray nozzles so that a double overlap of spraying water occurs. By this arrangement the plugging or failure of one spray will not affect the washing of the coal because the two adjoining sprays will still overlap.

The operation of the apparatus which has just been described, considered in some detail, is as follows: Coal is discharged from the float conveyor of the separator onto the receiving pan 41 and slate is discharged from the sink conveyor onto the receiving pan 42. The longer leg of the J-shaped screen frames is, from the receiving to the discharge end of the screen, of decreasing height, whereas the shorter leg, that which is attached to the spring boards, is of uniform height. As a consequence, spring boards of uniform length are used and the screen is held on an angle. The screen is divided at its mid-portion by a partition which prevents the separated

coal and slate from mingling. The driving mechanism reciprocates the screen at a rate which is consistent with the best performance and the materials are moved gradually from the receiving to the discharge end while being vigorously sprayed by a multitude of showers. The motion of the screen in combination with the sprays turns the coal repeatedly over so that all sides are exposed to, and thoroughly washed with, the cleansing liquid, effectuating a substantially 10 complete removal of the liquid which the material has carried with it. In order to prevent the stoppage of one shower from leaving the section of coal unwashed, the showers are arranged in overlapping series as shown in Figure 4—e so 15 that each particle of coal is ordinarily sprayed by the water from three nozzles.

The receiving pans 41—42 of the screen are solid, thereafter the screen becomes foraminous either by the punching of holes through the plate, 20 by the use of ordinary screens, or by other means. The final section of the screen is made of wedge-wire in order to drain from the coal and refuse substantially all entrained water before delivery to the discharge pans 47 and the divided boot 25 462. The screen could be all of one type of wire but the arrangement shown produces superior results, all factors considered. Water is preferably used for washing the material and it is forced under pressure into headers 442 from 30 whence it travels through the depending pipes to the spray pipes 448 and through the nozzles 449. The velocity of the spray is such that a considerable portion of the fluid is splashed from the material or the screen. The direction of the sprays would build up air currents passing from the receiving to the discharge end of the apparatus and considerable quantities of spray, containing recoverable liquid, would pass over the screen and down into the divided boot where it 40 would be lost and contaminate the coal. To prevent this, baffle plates 451 are attached before each spray pipe so that the mist from the preceding spray will be caught upon the face of the baffle, run down into channel 451, and be emptied 45 into the channels formed by the members 49 and 461 of the screen from whence they will pass toward the discharge end and be issued through orifices 461 upon the wedge-wire screen. Substantially all liquids which are brought into the 50 apparatus with the coal are removed from the coal and passed through the screens. In addition there is removed by the sprays a considerable quantity of fine solid particles, consisting mainly of earth and finely divided particles of 55 coal and slate, all below a certain size passing through the screens with the wash liquid.

When the liquids with entrained solids pass through the screens, they are prevented from reaching the sides of the tank by baffles 404, 60 plates 419, 420, 421, and 408. It will be observed that plates 419, which are rigid with the frame of the machine, have openings through which pass the bars 403—402 of the screen, the openings in the wall of plate 419 being of size to permit the reciprocating motion of the screen. To prevent the discharge of liquid through that opening into the seal the plates 421, of a size adequate to cover the said openings in all positions of the screen, are mounted on the rods 65 402—403 and a baffle plate 420 deflects any fluid flowing down the side of plate 419 over and beyond the said plate 421. All liquid which passes through the screen, consequently, falls upon and runs down the inclination of plate 454, which is 70 75

a plate having a surface which permits the maximum desirable transportation of the liquid. The plate 454 is terminated short of the side wall and the liquids drop therefrom at substantially 5 the top of riffle plate 456. They run down the said riffle plate, the solids tend to precipitate, and globules of heavy liquid tend to become larger globules so that, when the liquids have finally passed the length of the riffle plate, a partial separation of the constituents has been effected. The riffle plate is terminated short of the side wall 407 of the machine and the flow passes over the ends thereof and into the tank 406, all of whose bottom portions slope to the 10 central low point in the neighborhood of outlet 459. The sludge and some parting liquid settle in the vicinity of the opening 457 and the liquid which carries only comparatively fine particles of solid flows over the weir 410 into the other 15 section of the tank, being pumped through orifice 458 to a recovery system, as is more fully elsewhere described. The sludge is pumped through orifice 457 to the recovery system, which is elsewhere more fully described. If the sludge 20 has collected so thickly at the orifice 457 that the sludge pumps cannot draw it from the tank, a hose may be attached to pipe 459 and water under pressure used to force the sludge out of the chamber.

25 The screen is counterbalanced by the use of spring board supported counterweights driven by oppositely placed eccentrics from the same shaft. The covers which give admittance to the tank are water sealed by the use of flanged covers 30 which fit water filled channel members in the machine casing.

In order to drive the screen, which is inside the tank, from the driving gear, which is outside, without permitting the escape of vapors, 40 channel members partially filled with water are provided on each side of the machine. The screen frame is made J-shaped, each J projecting into the liquid within the said channels, and being shorter than they by the length of the 45 swing. The upper portion of the tank is then, so to speak, placed within the hook of the J so that its lower edge is beneath the water level in the channel. The J-shaped frame, consequently, reciprocates within a water seal which effectively prevents the escape of gas, and the previously described construction of the apparatus 50 prevents the contamination of the liquid in the said channels.

From the screen the coal and slate drop into 55 divided boot 462. Giving admittance to this boot are hermetically sealed covers 464. Hermetically attached to the boot on the one side is liquid-tight conveyor box 51 and on the other side a similar conveyor box 52. The boot thus becomes 60 two chutes, one for the coal and one for the slate. A description of one of these conveyors will suffice for both. 51 is the conveyor box in general, being a gas and liquid-tight tank made of metal or other suitable material; 53 is a hopper 65 within the said conveyor tank having an inclined wall 54 to direct the material which falls from the screen into the conveyor box at the angle which offers the least interference with the descending flights of the conveyor; 510 is 70 the inclined underside of the conveyor tank; 511 is a displaced portion of the said side; 512 is a foraminous section forming a continuation of the portion of the bottom 510, the portions 511 and 512 forming between them a space of a capacity adequate to take care of such liquid as

may be discharged to them from the solids which are carried out of the tank by the flights. 505 is a conveyor pan; 506 are openings in the lower portion of the conveyor pan; 507 is a section of wedge-wire screen forming the bottom of the 5 said conveyor pan at a point just short of the discharge lip thereof; 58 is the discharge lip of the conveyor pan over which the material is pushed by the conveyor; 59 is the supporting underlip of the conveyor tank; 513 is a flight conveyor; 514 are sprocket wheels over which the conveyor chains are trained; 516 is a motor mounted on the frame 517 of the conveyor; 518—519—520—521—522—523 are a combined power transmitting and speed reducing agency 10 consisting, in the modification shown, of a series of alternate large and small gears connected either directly or by means of flexible driving means such as chains or ropes. 524 is a wheel driven by means 523 and keyed to shaft 525 on 15 which are keyed the sprocket wheels 514; 526 are bearings on the tank which support the rod 525; 527 are parallel bearing blocks; 529 is a shaft journaled at one end with a loose fit in the 20 said bearing blocks 527 and at its other end in 25 complementary bearing blocks, not shown, at the other side of the conveyor box. 530 is a rod fastened at one end to the shaft 529 and having at its upper end a screw-threaded nut 532; 531 is a screw-threaded rod making operable 30 screw-threaded contact with the nut 532. One of these rods is attached to each end of the shaft 529. The rods 531 are mounted on a rod which transverses and is attached to the sides of the 35 tank. The conveyor may jump away from the pan due to the loose fit of the blocks and may be manually adjusted by nuts 532. 541 is an 40 opening in the base of the section 511 to which is attached a pipe, not shown, connected to the lower section of the conveyor whereby to return the liquid drained from the whole by the wedge-wire screen to the conveyor box at a lower point; 542 is an inlet pipe and valve through which liquid can be run into conveyor box; 543 is an 45 outlet pipe and valve at the bottom of the conveyor which permit the drawing off of such sludge as may form there. The pipe 543 is connected either to a waste pit or to the settling tank, which is elsewhere herein more fully described. 544 is a liquid box outside of the 50 machine; 545 is an overflow pipe within the said liquid box.

The operation of the apparatus is as follows: Coal is dropped from the discharge lip 48 of the screen through the divided boot and the hopper. 55 The hopper and the conveyor tank are filled to the level 546 with water or other suitable liquid. The coal is discharged into the water therefor above the hopper level and is directed by the inclination of the chute 54 to a place in proximity 60 to the descending flights of the flight conveyor. The coal passes through those flights and directly to the conveyor pan where it is picked up by the ascending flights, drained of liquid by passage over the wedge-wire screens and discharged over 65 the discharge lip 58. The liquid level in the apparatus is kept at the level 546 so that no fumes or liquids coming over the discharge end of the screen will be able to escape into the air. The liquid which is drained through the wedge-wire 70 screen fills up the space between the conveyor pan and the tank and thereafter passes through the screen 512 into the space below from which it is drained off by pipe 541 which returns it to the bottom of the conveyor tank or elsewhere. 75

Means are provided, not shown in these drawings, for blowing out the space between the conveyor pan and the bottom of the tank and consist of a nozzle through which water can be forced under pressure at 459 as has hereinbefore been described for other apparatus.

The liquids which wash the coal in the washing section remove from the coal and slate substantially all the heavy liquid and the fine particles 10 which are produced by abrasion or which are carried through the machine. In the settling tank at the bottom of the washing apparatus the liquid with fine suspensoidal matter is separated from the heavy sludge by the weir.

15 The system consists essentially of three settling or separating tanks interconnected, of which the first, located in the base of the washing section, makes a preliminary division between sludge and liquid containing light suspensoidal 20 matter, the second, called for purposes of differentiation the main settling tank, separates the comparatively light suspensoidal matter from the washing liquid and the third, called for convenience the sludge trap, receives the sludge 25 from both the first and second tanks.

Many modifications of the scrubbing process are possible. In addition to the sprays herein shown, sprays may be directed from beneath the screen to assist in the scrubbing of the coal. The 30 concentrated table or riffle board can be omitted, but its omission is inadvisable if preferred results are to be obtained. It has been stated in the literature that no static means has been designed which is capable of separating coal size 35 from wash water. It is believed that the method of separation which is disclosed represents the first successful separation of coal size and solids by a semi-static process. In this separation the riffle plate plays a valuable part by tending to precipitate the fines, coagulate the minute globules of parting liquid, and separate the water.

An advantage of this invention is the thorough removal from separated solids of adhering parting liquid. Another advantage is an apparatus 45 for washing separated solids with agitation under hermetical seal. Yet another advantage of the invention is that solids treated by this removal process are substantially free from all adhering parting liquid. Yet another advantage of the 50 invention is that loss of parting liquid by evaporation is avoided. Another advantage of the invention is the suspension of a movable screen within a hermetically sealed compartment. 55 Other advantages of the invention, both that of the process and apparatus, will be apparent from

a consideration of the specification and the claims.

As many apparently widely different embodiments of this invention may be made without departing from the spirit and scope thereof, it is 5 to be understood that we do not limit ourselves to the specific embodiments thereof except as defined in the appended claims.

We claim:

1. The process which comprises reciprocating 10 and turning mineral matter beneath concentrated sprays of water of high velocity, intercepting the splash from the sprays and the air current set up thereby, removing the minerals from the region of the sprays, and draining liquids therefrom. 15

2. Apparatus for the washing of solids which comprises an enclosure, a reciprocable screen within the enclosure, means to admit solids to the surface of the screen, a weir dividing the bottom of the enclosure beneath the level of the 20 screen, means to wash the solids on the surface of the screen, a riffle board beneath the screen, means to direct the washings which pass through the screen to the upper side of the riffle board, the said riffle board delivering the riffled washings 25 to one side of the said weir, and means for withdrawing materials from both sides of the said weir.

3. Apparatus for the washing of minerals which comprises an enclosure, sprays within the 30 enclosure, means beneath the sprays for reciprocating and turning the minerals, means to conduct the minerals to the said turning means, weir means beneath the said turning means to divide the said enclosure, and means beneath the said 35 turning means to agglomerate the constituents of the liquids that drain therefrom, and to direct the said liquids and agglomerated constituents to one side of the said weir.

4. An apparatus having a hermetically sealed 40 chamber with a wall, a reciprocable element within the chamber, an operating member and means outside the chamber to impart reciprocating motion thereto in a direction parallel to the wall, the operating member being connected to the reciprocable element, the wall having an opening at least as long as the path of reciprocation, a portion of the reciprocable system passing through the said opening in the wall, a water cup surrounding the opening, and a plate having a skirt 45 depending within the cup so that the opening can be sealed by filling the cup with liquid to a level above the bottom of the skirt. 50

HENRY L. ALEXANDER. 55
